Bartlett Brownell

UNITED STATES PATENT OFFICE.

EDWIN LUNDGREN, OF FREDERICK, MARYLAND, ASSIGNEE TO COMBUSTION ENGINEERING CORPORATION, OF NEW YORK, N. Y., A CORPORATION OF NEW YORK.

AUTOMATIC STOKER.

Application filed July 27, 1922. Serial No. 577,625.

To all whom it may concern:

Be it known that I, EDWIN LUNDGREN, a citizen of the United States, residing at Frederick, county of Frederick, State of Maryland, have invented a certain new and useful Improvement in Automatic Stokers, of which the following is a full, clear, and exact description.

The present invention relates to furnaces of the type in which the fuel while in the course of combustion is fed progressively toward a discharge outlet through which the refuse of the fuel is discharged, and has for its object to provide novel and improved fuel feeding means in a furnace of this character.

The several features of the invention will be clearly understood from the following description and accompanying drawings, in which,

Fig. 1 is a longitudinal sectional view of a portion of an underfeed furnace embodying the features of the invention in their preferred form;

Fig. 2 is a transverse sectional view taken on the lines 2—2 of Figs. 1 and 3;

Fig. 3 is a detail sectional elevation taken on the line 3—3 of Fig. 2; and

Fig. 4 is a detail sectional view, on an enlarged scale, taken on the line 4—4 of Fig. 3.

The furnace illustrated in the drawings is of the type of the one illustrated and described in the patent to Riley No. 1,322,822 dated November 25, 1919. As shown this furnace comprises an underfeed grate 2 and an overfeed grate 4 at the rear of the underfeed grate. The underfeed grate comprises a plurality of downwardly and rearwardly inclined retorts 6 arranged side by side and spaced apart, with the outer walls of the outer retorts spaced from the side walls of the furnace. Each of the retorts is provided with a bottom wall 8 and side walls 10. The bottom walls 8 of the several retorts form continuations of the bottom walls, respectively, of fuel hoppers 12 which are supported on an I-beam 14, the fuel from the hoppers being fed into the retorts by means of reciprocating plungers 16. On the upper edge of each of the side walls of the retorts is mounted a row of tuyère blocks 18, the rows of tuyère blocks mounted on adjacent walls of the retort being arranged side by side with their inner surfaces in sliding engagement, and the rows of tuyère blocks

mounted on the outer walls of the outer retorts extending over the spaces between the outer walls and the side walls of the furnace. The overfeed grate is made up of a plurality of sections arranged side by side, each of which is associated with one of the side walls of one of the retorts and these parts together with the row of tuyère blocks supported on the side wall are adapted to be moved together as a unit back and forth in a substantially horizontal direction so as to effect the feeding of the fuel progressively while in the course of combustion, and the discharge of the refuse of the fuel into an ash pit 20 which is located at the rear of the overfeed grate. To enable said units to be thus moved back and forth, each overfeed grate section is mounted on a shoe 22 adapted to slide horizontally on a support 24, the lower or rear end of the associated retort side wall being pivotally connected at 26 to the shoe and its upper or forward end being mounted to slide on the upper edge of the I-beam 14. The means for actuating the several movable units as above described comprise links 28 connecting the forward ends of the side walls of each retort with the feeding plunger 16 associated with the retort. Each of the shoes 22 carries the upper or forward end of a refuse discharging device 30 which extends downwardly into the ash pit 20 and cooperates with a clinker crushing roll 32 mounted in the ash pit. Except as hereinafter described, the parts above referred to may be and preferably are the same as corresponding parts of the stoker illustrated and described in said patent to Riley No. 1,322,822 to which reference may be had for a more complete description of the same.

In said patented construction the movable units comprising the side walls of the retorts and their respective rows of tuyère blocks and overfeed grate sections, have the same fuel agitating and feeding action at the forward portion of the fuel bed as at the rear portion thereof, which is objectionable, particularly in furnaces having relatively long retorts, as it is necessary in order to secure the maximum efficiency of performance that the fuel agitating and feeding action shall be greater at the forward portion of the fuel bed than at the rear portion. In order to overcome this disadvantage of said prior construction each of said movable units of

the furnace illustrated in the drawings is divided transversely into two sections and connections are provided between the sections so that as the upper or forward section is moved back and forth by its associated plunger 16, a back and forth movement of less amplitude will be imparted to the rear section, said connection between the sections having provision for adjustment to vary the difference of the amplitude of the movements of the two sections to meet different conditions. As shown, each of the side walls of the retorts is divided transversely in a horizontal plane as indicated at 32 into two sections 34 and 36. The forward end of each rear section 36 is mounted on I-beams 40 extending between the side walls of the furnace, the lower edge of the section having a horizontal portion 38 in sliding engagement with the tops of the I-beams. The rear end of the forward section 34 is supported by the forward end of the section 36, the lower edge of the forward section having depending guiding flanges 42 at the line of division between the sections which engage inwardly turned flanges 44 on the upper edge of the associated rear section 36. The connections between the sections 34 and 36 of each side wall of the retorts comprises a depending lug 46 on the outer side of the forward section 34 which is interposed between two spaced abutment screws 48 that are screw-threaded through lugs 50 on the rear section 36. With this construction it will be apparent that upon actuation of the reciprocating plungers 16 to feed the fuel from the hoppers 12 into the retorts that back and forth movements will be imparted to the several forward sections 34 and to the tuyère blocks supported thereby, and that back and forth movements of less amplitude will be imparted to the several rear sections 36, to the tuyère blocks supported thereby and to their associated overfeed grate sections. By adjusting the abutment screws 48 the lost motion between the sections and consequently the difference in the amplitude of the movements imparted to the forward and rear sections 34 and 36 of each side wall of the retorts may be varied as desired.

It will be evident to those skilled in the art that although the underfeed grate of the stoker illustrated in the drawings is made up of but two movable sections, the invention is not confined to a two section construction of the underfeed grate, it being only necessary that there shall be at least two such sections; and also that my invention permits of various modifications without departing from the spirit thereof or the scope of the appended claims.

What I claim is:

1. A furnace having, in combination, an underfeed grate and an overfeed grate at the rear of the underfeed grate, said underfeed grate having two sections arranged one behind the other and movable longitudinally of each other, connections between the rear section and the overfeed grate so as to cause them to move together, means for imparting a back and forth movement to one of said sections, and connections between said sections for imparting a back and forth movement to the other section of a different amplitude than said movement imparted to the former section.

2. A furnace having, in combination, an underfeed grate, an overfeed grate at the rear of the underfeed grate, said underfeed grate having two sections arranged one behind the other and movable longitudinally of each other, connections between the rear section and the overfeed grate, and means for imparting a back and forth movement to said sections having provision for adjustment to vary the amplitude of the movement of one of said sections with relation to the other section.

3. An underfeed furnace having means for supporting and feeding fuel while in the course of combustion comprising a downwardly inclined retort having each of its side walls divided transversely into two sections, one section of each wall being movable longitudinally with relation to the other, tuyère structures mounted on each of the side walls, and means for imparting a back and forth movement to said movable section with relation to the other.

EDWIN LUNDGREN.
